UNITED STATES PATENT OFFICE.

ANSEL G. COOK, OF HARTFORD, CONNECTICUT.

PLASTER-BANDAGE MACHINE.

Application filed January 29, 1923. Serial No. 615,603.

To all whom it may concern:

Be it known that I, ANSEL G. COOK, a citizen of the United States, residing at Hartford, in the county of Hartford and

5 State of Connecticut, have invented a new and useful Improvement in Plaster-Bandage Machines, of which the following is a specification.

This invention relates to apparatus designed to prepare and roll plaster bandages, that is, those bandages which consist of a fabric, commonly crinoline, with the interstices of the fabric impregnated with plaster of Paris, that are used by surgeons in 10 hospitals for wrapping broken bones, limbs and joints. Too little plaster makes the bandages ineffective. Too much plaster renders the bandages bulky and difficult to uniformly soak. Bandages loosely rolled 15 are not easily handled and those too tightly rolled will not soak satisfactorily.

Machines have been proposed for making such bandages but mostly such machines have been complicated, requiring the service 20 of skilled operators and owing to the nature of the plaster they have failed to produce uniformly satisfactory bandages, as well as being expensive to manufacture. Consequently it has been common practice 30 in hospitals to make these bandages by running out a length of the fabric, such as crinoline, and rub powdered plaster of Paris into the interstices of the fabric by hand, which is a slow, tedious, and on the whole an 35 unsatisfactory method of procedure.

The object of the present invention is to provide a very simple and inexpensive apparatus particularly adapted for hospital service, that can be successfully manipulated 40 so as to rapidly produce bandages charged with just the required quantity of plaster that are uniformly rolled with the desired tension for successful soaking, and satisfactory application by an unskilled operator, as a nurse.

This object is attained by arranging on a bed means for receiving an uncharged roll of bandage fabric and a reel for rolling the plaster charged fabric, with means intermediate these elements for ironing the charge of plaster into the interstices of the fabric as it is drawn from the uncharged roll to the winding reel, such ironing means being adjustable in order that the required 55 charge may be forced into the fabric and being movable to permit a quick cleaning of

the bed along which the fabric is drawn.

In the accompanying drawings Figure 1 shows a plan of an apparatus which embodies the invention. Fig. 2 shows a front elevation of the apparatus. Fig. 3 shows a vertical section through the means for ironing the plaster into the interstices of the fabric.

In the apparatus illustrated there is a bed 1 provided with a sanitary finish, and that has a tray-like space 2 at the back on which the powdered plaster of Paris to be used may be piled. Near one end on the top of the bed are two posts 3 the upper ends of which are forked for receiving the spindle 4 which is thrust through the uncharged roll of bandage fabric. The spindle has a handle 5, and two collars 6 arranged to prevent the spindle from longitudinal movement when it is laid with the bandage roll in the notched upper ends of the posts. At the other end on the top of the bed are upright brackets 7. In these brackets spools 8 are rotatably mounted on suitable bearings. In each spool are a pair of holes 9. The winding reel shown comprises two pairs of rods 10 that project from a hub 11 to which is fastened a crank arm 12 with a handle 13. The reel rods are designed so that they may be freely thrust through or withdrawn from the pairs of holes in the rotatable spools mounted in the brackets.

Between the spindle supports and reel carrier is the ironing member. This ironing member consists of a weighted plate 14 provided with arms 15 that are hinged by pins 16 to lugs 17 secured to the top of the bed between the ironing member and the reel. At the lower edge of this plate is a foot 18 the bottom face of which is inclined with relation to the plane of the upper face of the bed. The narrowest part of the opening between the foot and the bed is toward the reel. Set screws 19 are threaded through the foot against the upper surface of the bed, and held by clamping nuts 20 for adjusting the height of the opening between the under side of the foot and the top of the bed.

In use the spindle is thrust through an uncharged roll of bandage fabric, as crinoline, of common length and width and laid in the notches of the spindle supports. The free end of the fabric is drawn from the spindle over the bed and beneath the ironing member. After a quantity of plaster

of Paris is deposited on the fabric in front of the ironing member the fabric is drawn along and the free end connected with the reel by inserting the end of the fabric between the two rods. The reel is then turned, desirably counter-clockwise, so as to draw the fabric beneath the ironing member and wind it up on the reel. As the fabric passes under the heavy ironing member it carries with it the desired quantity of the powdered plaster of Paris, and this plaster, owing to the inclined under face and weight of the ironing member, is pressed into the interstices of the fabric so that the powder will remain in the fabric while the bandage is being wound up on the reel. The ironing member, of course, spreads, the plaster uniformly and prevents an undesirable surplus from being carried along on the surface of the fabric. After the entire strip of fabric has been filled with plaster and wound upon the reel the bandage roll is grasped by the hand and the reel drawn out axially. When the charged bandage has been removed the ironing member is swung over toward the reel leaving the bed free to be wiped clean before starting the filling of another bandage.

This apparatus is inexpensive to build and can be successfully manipulated by an unskilled operator. The plaster is uniformly spread throughout the interstices of the fabric, the desired quantity is thoroughly ironed into the interstices of the fabric, and the bandage is wound with the required tension necessary for it to absorb the proper amount of water when it is soaked, as it is just before use. Furthermore, the reel rods leave an opening in the center of the roll so that the water will permeate from the inside as well as the outside ensuring an even wetting.

The invention claimed is:

1. A bandage machine comprising a bed, means for removably supporting an uncharged roll of bandage fabric, a removable reel for winding the charged bandage fabric, a weight intermediate said support and reel for ironing plaster into the interstices of the fabric as the bandage strip is drawn from the support and wound upon the reel, and means located between the reel and weight hinging the weight at each side of the bandage path to the bed whereby the weight may be swung on said hinging means over the bandage path toward and from the reel.

2. A bandage machine comprising a bed, means for supporting an uncharged roll of bandage fabric, a reel for winding the charged bandage fabric, and a weighted

member hinged at each end to the bed between the reel and weight for ironing plaster into the interstices of the fabric as the bandage strip is drawn from the support and wound upon the reel. 65

3. A bandage machine comprising a bed, means for supporting an uncharged roll of bandage fabric, a reel for winding the charged bandage fabric, and a freely swinging weight hinged to the bed by pivots at each side of the bandage path from said supporting means to the reel and intermediate said support and reel for ironing plaster into the interstices of the fabric as the bandage strip is drawn from the support and wound upon the reel. 70 75

4. A bandage machine comprising a bed, means for supporting an uncharged roll of bandage fabric, a reel for winding the charged bandage fabric, a weighted member hinged to the bed by pivots at each side of the bandage path from said supporting means to the reel and intermediate said support and reel for ironing plaster into the interstices of the fabric as the bandage strip is drawn from the support and wound upon the reel, and adjusting screws 80 85 threaded through the weight for determining the height of the space between the bottom of the weighted member and the top of the bed. 90

5. A bandage machine comprising a bed, means for removably supporting a spindle at one end of the bed, means for supporting a reel at the other end of the bed, arms pivoted to the bed at each side of the path from one support to another, and a weight attached to said arms intermediate said supports, said weight having an inclined 95 100 105 under face for ironing plaster into the interstices of the fabric as a bandage strip is drawn beneath the weight.

6. A bandage machine comprising a bed, means for supporting a reel near one end of the bed, means for rotating the reel and thereby drawing a strip of bandage fabric across the bed and winding it upon the reel, arms pivoted to the bed at each side of the path of bandage fabric being wound upon the reel, a weight attached to said arms, said weight having an inclined under face for ironing plaster into the interstices of the fabric as the bandage strip is drawn beneath the weight, and adjusting screws 110 115 120 loosely supporting the weight and determining the distance between the inclined under face of the weight and the top of the bed, the opening between the bottom of the weight and top of the bed being contracted toward the reel.

ANSEL G. COOK.
